(57) **CLAIM**

The ornamental design for a container and lid of a food processor, as shown and described.

DESCRIPTION

FIG. 1 is a bottom, front and right side perspective view of a container and lid of a food processor of our design;

FIG. 2 is a front elevation view thereof;

FIG. 3 is a rear elevation view thereof;

FIG. 4 is a left side elevation view thereof;

FIG. 5 is a right side elevation view thereof;

FIG. 6 is a top plan view thereof; and,

FIG. 7 is a bottom plan view thereof.

The broken lines depict portions of the container and lid of a food processor that form no part of the claimed design.

1 Claim, 4 Drawing Sheets
